UNITED STATES PATENT OFFICE.

CARL A. JOERISSEN, OF WASHINGTON, DISTRICT OF COLUMBIA.

COMPUTING-MACHINE.

1,011,125.

Specification of Letters Patent. Patented Dec. 5, 1911.

Application filed July 21, 1911. Serial No. 639,838.

To all whom it may concern:

Be it known that I, CARL A. JOERISSEN, a citizen of the United States, residing at 1206 F street northwest, in the city of Washington, District of Columbia, have invented certain new and useful Improvements in Computing-Machines, of which the following is a specification.

While this invention is applicable to computing machines in general, it is designed more particularly for embodiment in the type of machine disclosed in United States Letters Patent No. 905,421, granted December 1, 1908, upon the invention of Hans 15 Hanson, to which reference is here made for a full disclosure of any part or parts not immediately concerned with the present invention, but which may nevertheless be necessary to rendering the machine completely 20 operative for all its intended purposes.

The object of the present invention is to adapt machines such as shown in said Letters Patent, for use in subtracting and dividing as well as adding and multiplying.

To these ends the invention consists broadly, in reversing the direction of drive between the register elements and their actuating elements and rendering temporarily ineffective their zeroizing stops so that with 25 any desired setting of the decimal order registering bars, it is merely necessary to adjust the subtraction or division key if the expressed number is to be deducted (once in subtraction or a number of times in division), whereupon the usual throw of the operating lever will cause the rotation of the register disks to take place in a direction opposite to that in which addition takes place and the result will be a subtraction or 30 division.

In the accompanying drawings:—Figure 1 is a vertical longitudinal section of that part of the patented computing machine which is immediately concerned with the 45 present invention. Fig. 2 is a plan view of part of the computing mechanism. Fig. 3, an end view of Fig. 2 showing the carrying device. Figs. 4 and 5 are also end views of Fig. 2 seen from the opposite side of Fig. 2. Fig. 6 is a plan view of another embodiment 50 of the carrying device. Fig. 7, an end view of Fig. 6. The following figures are in larger scale: Fig. 8 is a detail view of the zeroizing stop by means of which a register

wheel is arrested when it reaches its zero 55 position. Fig. 9 is a detail view of ratchet wheel with its mounting in transverse section. Fig. 10, a detail view of the reversely acting pawls and ratchet wheel as in Fig. 9 adapted to be brought into operation with 60 either one of the pawls. Fig. 11, a plan view partly in section of Fig. 10, with a different shifting device to the one shown in Fig. 2. Fig. 12 is a modification of Fig. 10 showing two ratchet wheels acting in opposite direction using only one pawl. Fig. 13 is an elevation of Fig. 12. Fig. 14 is a detail view of the means for holding the shaft in different axial adjustments. Fig. 15 is a section in large scale of the ratchet 70 and register wheels shown in Fig. 2.

For convenience in comparing the present improvements with the aforesaid Letters Patent 905,421 upon which the illustrated embodiment of the present invention 75 is based, the parts are as far as practical designated by the same reference characters as in said patent.

The decimal order register bars c , which carry the unit pins c^{10} are adapted to be depressed, individually, by means which have been fully described in the above referred to patent for the purpose of determining the throw of the register bars and subsequently the angular rotation of the register wheels. 85 The operating carriage c^{11} is designed to impart forward movement to the register bars, by engagement with the particular unit pins that are for the time being depressed into the path of the bar c^{12} of said 90 carriage, and to impart movement in the return direction by the engagement of the bar c^{13} with the shoulder c^{13x} .

On the shaft a^1 , Figs. 1, 2, 12, 13 and 14 is mounted a sleeve a^{1x} . a represents the register wheels, which are loosely mounted upon the sleeve a^{1x} . A number of key pins a^{19} are fixed in a straight line in the shaft a^1 and projecting radially on each side thereof. In the sleeve a^{1x} are located a like number of L shaped slots on opposite sides, through which the pins a^{19} project into a recess in the adjoining sides of two oppositely acting ratchet wheels a^{3x} , which are joined together as one and are free to rotate 100 on the sleeve a^{1x} , but may be displaced axially relative to said sleeve by means of said pins a^{19} and shaft a^1 . A longitudinal move- 105

ment of the shaft a^1 accomplishes the change from addition to subtraction, Figs. 1 and 2. One side of the L shaped slot runs parallel with the axis of the shaft and the other perpendicular thereto. These pins are so located relative to the clutch balls t^{10} , that with the ends of the pins standing at the outer gunion shank of the L, the clutch balls are forced up by their springs into the spiral groove of the star wheels a^5 ; see Fig. 8 but with the ends of the pins located in the angle of the L slot the balls will be re-tired. For subtraction the shaft a^1 is thrown out axially bringing with it the pins a^{19} and the ratchet wheels a^{3x} until they come to the extreme end of the shank of the L slot. This will be accomplished by turning the handle D which, having an eccentric a^{20} will push the plate D^2 outward bringing the shaft a^1 with it. As shown in Fig. 14, the shaft a^1 is retained in either of its two positions by means of a ball clutch. On turning the handle D back the spring d^5 will return the shaft to its normal or adding position. A yielding pawl a^4 , Figs. 12 and 15, carried by the register wheel a , engages one or the other of said ratchet wheels a^{3x} . Keyed to said ratchet wheels, so as to always rotate together, is a pinion a^2 which receives its movement, in the usual manner, from the register bars c , on the turning of the lever c^{20} . A star wheel a^6 , Fig. 8, is rigidly connected with each of the register wheels, and has ten teeth which mesh with a three toothed star wheel a^{10} of the carrying mechanism, see Figs. 1 and 2. To hold the star wheel a^6 in its position after turning, a dog a^6 actuated by a spring is made to enter between the teeth of the star wheel.

Instead of the double ratchet wheel a^{3x} , I might use the following arrangement. The register wheels a are keyed to the arresting pinions or star wheels a^5 , Figs. 10 and 11 so as to revolve with the arresting pinions a^5 but to have a slight axial displacement relative thereto. A single ratchet wheel a^3 built in one piece with or rigidly connected to pinion a^2 , engages a pawl a^4 , when turned in one direction, see Figs. 10 and 11, mounted on said register wheel a , said pawl a^4 yielding when the ratchet is turned in opposite direction to which the register wheel a is revolved for addition. To reverse the motion of the register wheel a , this wheel has to be displaced axially until pawl a^{4x} engages the ratchet wheel a^3 simultaneously disengaging pawl a^4 . The axial displacement of the register wheel a is done by means of one or more combs A which are situated across the machine parallel with the shaft a^1 and has a longitudinal movement limited by stops A^2 . The spacing of the teeth A^1 of said comb is equal to the distance between the register wheels a ; and the teeth grip on both sides of each register

wheel so that the wheel partakes of any movement lengthwise of the comb, which is operated by hand from the outside of the machine and has a spring catch A^4 to positively hold it in one of two different positions. A yielding dog a^6 is supplied for each register wheel engaging between the teeth of the star wheel a^5 , as before.

In shaft a^1 Figs. 2 and 8, in the same transverse planes as the star wheels a^5 and of the same number, are located clutch balls or clutch pins t^{10} , which are pressed outwardly by helical springs. Opposite each clutch is a hole provided in the sleeve a^{1x} , so that on partial turning of the sleeve relative to the shaft a^1 , the clutches are made to retire below the surface of the sleeve which is its normal position. The central opening of the star wheel a^5 , has a spiral groove, see Fig. 8, running out from its circular part, forming an abrupt shoulder at one point. The clutch t^{10} will engage said shoulder on the partial turning of the sleeve which allows the clutch to protrude. A similar clutch is provided for the zeroizing pinion C^6 . At one end of the sleeve a^{1x} is located a disk C^{15} which is keyed on the sleeve and serves, assisted by the dog A^6 , engaging one of the two notches in the disk C^5 , to hold the sleeve in either position for retiring or freeing the clutch balls t^{10} .

In the normal operation of the machine as heretofore constructed, the outward stroke of the bar c rotated the pinion a^2 and wheel a^5 without affecting the register wheel a , which was held in its zero position against backward rotation by the clutch ball t^{10} , but when the register bar c returned to its normal position, rotation was imparted to the wheel a to an extent accurately determined by the length of the outward stroke of the register bar. Thus movement of the register wheels corresponding to the addition to be effected, was accomplished. In order to make the register wheels susceptible to backward rotation without reorganization of the actuating parts that have been described, I provide a means for retiring the clutch ball t^{10} so that the wheel a can move backward past the zero point under the outward movement of the register bar c and at the same time bring the ratchet wheel a^3 under the influence of the pawl a^{4x} , so that the wheel a is forced to move in a backward subtracting direction; but when bar c returns to normal position, the wheel a will be arrested by the dog a^6 and its movement resisted while the pawl a^4 drags over the projections of the ratchet wheel a^3 .

For liberating the ratchets t^{10} , the reversing gear shown in Figs. 1 and 2 and in detail in Fig. 5 has been provided. A key B which is normally held in its raised position by a spring B² has a projecting toe B³ which engages a pin B⁴ at one end to a rocking

- lever B⁴. On the sleeve a^{1x} is rigidly attached opposite said lever B⁴, a short finger C so that when the key B is pushed down the pin B⁵ will be depressed and the opposite end of lever B⁴ raised forcing finger C and sleeve a^{1x} around part of a revolution, so that the clutch balls t¹⁰ stand ready to run out along the spiral groove in the star wheels. On the partial rotation of the sleeve 10 a^{1x} above described, the clutch ball t¹⁰ will be pressed outwardly into the spiral groove, of the zeroizing pinion C⁶ by the spring behind it, until meeting the offset formed by this spiral in the circular opening of the 15 pinion C⁶. If the crank c²⁰ now is turned the register bar C⁴ will turn the pinion C⁶ one complete revolution. Pinion, sleeve and shaft now being coupled together, the 20 clutches t¹⁰ will engage the star wheels a⁵ one by one during the rotation of the shaft, depending on their position, and turning their respective register wheels with them. On the return stroke of the register bar C⁴, the pinion C⁶ runs free, the register wheels 25 being held stationary meanwhile by the engagement between dogs a⁶ and star wheel a⁵. Near the end of the return stroke of bar C⁴ a projection C² will engage the finger C³ attached to the sleeve a^{1x}, whereby the ratchet 30 balls t¹⁰ will be forced to retire out of engagement with the star wheels a⁵ and the pinion C⁶.
- With the construction above described the ratchet wheels may be operated in a direction opposite to that referred to and may be made to accomplish all other purposes which are accomplished in other machines as well, so that the machine is adapted by the present invention for subtracting and dividing 35 as well as adding and multiplying.
- The carrying mechanism consists of a number of fingers a¹⁵ and A¹⁵, see Figs. 2, 3 and 4 attached to a shaft a¹⁴. The fingers a¹⁵ for addition are placed in a spiral on the 40 shaft a¹⁴ opposite to the corresponding pinions a⁹ commencing from the end opposite the digits, so that on revolving the shaft a¹⁴ the digit finger first comes into operation, next the tens, thereafter the hundredths. The subtracting fingers a¹⁵ are placed in a 45 single spiral running in the opposite direction, and each one offset about the thickness of the finger to one side of the adding finger a¹⁵. A groove a^{9x} is cut in the circumference 50 of each pinion a⁹ so as to allow, on the rotation of shaft a¹⁴, the subtracting fingers a¹⁵ only engaging the respective pinions at the time. To 55 set the carrying mechanism for subtraction the shaft a¹⁴ is drawn out to one side with the same eccentric a²⁰ by which shaft a¹ is operated. The finger A¹⁵ will now come 60 into engagement with the teeth of pinion a⁹, the fingers a¹⁵ simultaneously being brought 65 out of engagement. As the spiral of the fin-
- gers A¹⁵ runs opposite to the spiral of the fingers a¹⁵ the carrying will be operated in opposite direction, ending with the digit register wheel instead of starting with it. The spring D⁵ at one end of the shaft a¹⁴ 70 will bring the fingers of the carrying mechanism back to their normal position for adding. For driving the carrying mechanism two pinions D⁶ and D⁷, Figs. 2 and 4, are provided, in the usual manner operated by a 75 rack D⁸ engaging both pinions simultaneously. The shaft a¹⁴ has a similar ball clutch D⁹ as the ball clutch t¹⁰ above described, with a spiral groove to each of the pinions D⁶ and D⁷. These pinions are placed on 80 the shaft a¹⁴ with the spiral grooves running in opposite directions so that the ball clutch D⁹ will engage only one of the pinions at a time, the other pinion running idle.
- As shown in Fig. 2 the mechanism is set 85 for adding. By displacing shaft a¹⁴ toward the right of the figure the ball D⁹ will be taken out of engagement with pinion D⁶ and brought into engagement with pinion D⁷ whereby the shaft a¹⁴, with the fingers will 90 be rotated on the return stroke only of the rack D¹², for subtraction.
- In Figs. 6 and 7 a different construction 95 of the carrying mechanism has been shown wherein a single row of fingers A¹⁶ is utilized. In this case the fingers A¹⁶ have each a hub which surrounds the shaft A¹⁴, and each hub has a tooth A¹² engaging a recess A¹³ in the hub of the next finger. The recess A¹³ is wider than the tooth A¹², so that, 100 when the mechanism is changed from addition to subtraction, by displacement of the shaft as before, the fingers are made to rotate slightly on shaft A¹⁴, until they are positioned in an opposite spiral similar to that 105 formed by the fingers A¹⁵ in Fig. 2.
- The star wheel a¹⁰, Figs. 1, and 2, of the carrying mechanism has only three teeth, which are brought in mesh with the star wheel a⁵ of the register wheel of the next 110 higher denomination whenever turned by a finger a¹⁵ (or A¹⁵ during subtraction). Built in one with the star wheel a¹⁰ is the carrying pinion a⁹, with nine teeth, six of which in pairs, have the full width of the pinion. An 115 annual groove a^{9x}, however, cuts the teeth in two, for allowing the idling, subtracting fingers A¹⁵ to pass. The remaining three teeth, located opposite the teeth of the star wheel a¹⁰ have the width limited by said groove and said star wheel, so that the adding finger a¹⁵, located on the other side of said groove, may pass by without turning the pinion a⁹ until said pinion has been partially turned by the register wheel a. For 120 this purpose, a spur A²⁰ has been provided on the register wheel a, projecting beyond its circumference and engaging between two of the full teeth of the carrying pinion, once for each of its revolutions, or when the reg- 125 130

ister wheel is turned from nine to zero. The carrying pinion a^9 is then turned by said spur and one of its teeth intercepts the finger a^{15} , so that, on the swinging of the finger a^{15} the pinion a^9 turns, and with it the star wheel a^5 which subsequently advances the star wheel a^5 and register wheel of the next denomination, one space. A set of spring operated dogs a^{12} is provided engaging between the full teeth of the carrying pinions a^9 to hold them in position.

A retarding device is shown to the right of Fig. 2 and also in Fig. 3. It comprises a spring D^3 pressing on a knurled or toothed wheel D^4 , keyed to shaft a^1 , causing friction in whatever direction the shaft is turned.

The adding operation has been fully described in the patent above referred to. As shown in the drawing the machine is ready for adding. To zeroize proceed as follows:

First: Depress zero key B which in the usual manner will throw the rack C^4 into engagement with the operating mechanism. Simultaneously the key B operates the lever B^4 , through projection B^3 and pin B^5 , impinging finger C whereby the sleeve a^{1x} , together with the disk C^5 will be slightly revolved shifting the dog A^6 from one notch in said disk to another. This will allow clutch t^{10} to run out along the spiral groove engaging the pinion C^6 .

Second: Turn the operating lever c^{20} by hand or by motor thereby running the zeroizing rack C^4 out and rotating the carrying mechanism. This will revolve the zeroizing pinion C^6 with the disk C^5 and also by means of the other clutch t^{10} engage one by one, depending on the position that they happen to have, the star wheels a^5 and with them the register wheels a , turning them to nines.

Third: On the back stroke of the lever c^{20} and the rack C^4 the projection C^2 by means of the finger C^3 turns the sleeve a^{1x} slightly backward to its normal position when the dog A^6 again will engage the first notch of the disk C^5 so that at the end of the stroke the clutches t^{10} , both of the register wheels and of the zeroizing mechanism will be retired and made inoperative and the register wheels will all show zero.

To change the mechanism from adding to subtracting position proceed as follows: Displace axially both the shafts a^{14} and a^1 of the carrying and totalizing mechanisms by means of the handle D, eccentric a^{20} and connecting plate D^2 . The shaft a^1 will simultaneously displace all the pins a^{19} and with them the double ratchet wheels a^{3x} thereby bringing the teeth of the subtracting ratchet wheel into engagement with the yielding pawl a^4 and the adding ratchet wheel out of engagement therewith. By this means the racks c will operate on the return stroke instead of the outward stroke so that

the register wheels will revolve in the order from the higher to the lower numbers for subtraction.

The machine is now ready for subtraction and the following operation has to be performed:

First: Turn the lever c^{20} as before when all the racks c that happen to be in engagement with pins a^{10} will run out and revolve the pinions a^2 and ratchet wheels a^{3x} , but as the inclined side of the teeth of the wheels a^{3x} turn toward the yielding clutch, balls t^{10} , the star wheels a^5 , register wheels a and the dogs a^6 will remain stationary.

Second: On the return stroke of the crank c^{20} the racks c of the registering mechanism will operate as the teeth of the ratchet wheels a^{3x} will now turn the register wheels along with them. The pins c^{10} will thereupon be pushed up in the usual manner.

Third: Contrary to the operation for adding, for subtraction two strokes of the crank will be necessary. On the second stroke, the racks c , now being left behind, as the pins c^{10} have been pushed back on the previous stroke; the pinions a^2 will run idle but the carrying mechanism will operate the pinions a^9 by means of the fingers A^{15} in the opposite order to what is done in the adding operation, so that the unit finger A^{15} will operate last instead of first. The pinions a^9 will, in their turn, revolve the register wheels a in the same manner as during the adding operation but in opposite order.

Fourth: On the back stroke of the lever c^{20} both the carrying and the totalizing mechanisms remain idle.

If the mechanism shown in Figs. 10 and 11 with a single ratchet wheel and the two pawls a^4 and a^{4x} is applied on the machine, the comb A has to be shifted instead of shaft a^1 in a similar manner by means of an eccentric a^{20} or by drawing it out by hand whereby the register wheels a bring with them the two pawls a^4 and a^{4x} , which then are shifted, the one out of, and the other into engagement with the single ratchet wheel a^3 , the procedure otherwise being the same.

I claim:

1. In a computing machine, the combination of the registering mechanism, and driving means for said registering mechanism acting in relation thereto in two directions, of means for causing the driving connections to idle in one direction and to drive the registering mechanism in the other direction, and manually controlled means for reversing the directions of said idling and driving means at will.

2. In a computing machine, the combination with the registering mechanism and the driving connection therefor, including a ratchet, one member of the ratchet being constructed with two oppositely acting parts and the other member of the ratchet adapted

for movement axially into coöperation with either of the displaced parts of the ratchet at will.

3. In a computing machine, the combination with the registering mechanism and the driving connection therefor, including a ratchet, one member of the ratchet being constructed with two oppositely acting parts and the other member of the ratchet adapted for movement axially into coöperation with either of the displaced parts of the ratchet at will, and means imparting such axial movement comprising a comb having fingers engaging said part of the ratchet to be displaced.

4. In a computing machine, the combination with the registering means and driving connection for said registering means including a ratchet; said ratchet having one of its members displaced and constructed to act in opposite directions; one of said members being a disk movable axially to bring either of the displaced members into coöperation at will and means provided to effect such axial movement in both directions of said disk comprising a shaft having radial pins positioned to engage said disk.

5. In a computing machine, the combination of a shaft, a registering member mounted loosely on said shaft, a clutch between said registering member and the shaft, constructed to arrest relative rotation between said member and shaft in one direction only, and means for retiring the clutch to permit rotation of the registering member in the direction normally opposite the clutch.

6. In a computing machine, the combination of a shaft, a registering member mounted loosely on said shaft, a clutch between said registering member and the shaft constructed to arrest relative rotation between said member and shaft in one direction only, and means for retiring the clutch to permit rotation of the registering member in the direction normally opposite the clutch, comprising a sleeve surrounding the shaft and having an opening through which the clutch works but having movement relative to the shaft to bring the opening out of register with the clutch and adapted by said movement to depress the clutch out of operative position.

7. In a computing machine, the combination of a registering member, a shaft upon which said registering member is loosely mounted, a clutch interposed between said member and shaft and constructed to oppose relative rotation between said member and shaft in one direction only, the driving connection of the registering member including reversely acting ratchets, means for substituting one ratchet for the other in the driving connection and means for simultaneously retiring the clutch between the registering member and the shaft.

8. In a computing machine, a shaft, a registering wheel mounted on said shaft; a clutch interposed between said registering wheel and said shaft constructed to oppose relative rotation in one direction only, a sleeve surrounding the shaft rotatable relative thereto and constructed to retire the clutch between the shaft and registering member, a driving connection for the registering member including reversely acting ratchets; and a connection between said sleeve and said ratchets adapted to throw either ratchet into driving connection.

9. In a computing machine, a shaft, a registering wheel mounted on said shaft, a clutch interposed between said registering wheel and said shaft constructed to oppose relative rotation in one direction only, a sleeve surrounding the shaft rotatable relative thereto and constructed to retire the clutch between the shaft and registering member, and a toe rigidly attached to said sleeve, a rocking lever actuated by depressing a key, said rocking lever coöperating with said toe to partly rotate said sleeve in order to put the clutch in action; and a projecting member on the driving rack coöperating with another toe also rigidly attached to said sleeve for the purpose of a partial turn in the opposite direction to put said ratchet arrangement out of action.

10. In a computing machine, a carrying mechanism comprising a shaft, a plurality of fingers radially projecting from said shaft; and disposed relatively to each other in a spiral, said fingers being adapted to be shifted on said shaft to form an oppositely running spiral, a carrying pinion actuated by said fingers for the adding operation when said fingers are rotated in one direction; said carrying pinion being operated for subtraction when said fingers are arranged in an oppositely running spiral and are rotated in the opposite direction.

11. In a computing machine, comprising a totalizing and carrying mechanism, a registering wheel, a spur on said registering wheel projecting beyond its circumference, a set of carrying fingers, a carrying pinion, said spur adapted to engage said pinion during its revolution and to revolve the pinion so as to place one of its teeth in readiness for engagement with one of said fingers when said fingers are turned in one direction for addition, and in opposite direction for subtraction.

12. In a computing machine having carrying mechanism, a shaft, for the carrying mechanism, a plurality of fingers radially projecting from said shaft and disposed relative to each other in a spiral; and a like number of radial fingers similarly mounted on said shaft but arranged in an oppositely running spiral from the first mentioned fingers.

13. In a computing machine, having carrying mechanism, a shaft for the carrying mechanism comprising a plurality of fingers radially projecting from said shaft and disposed relative to each other in a spiral and adapted to operate the registering mechanism when run in one direction, and a like number of radial fingers similarly mounted on said shaft but arranged in an oppositely running spiral from the first mentioned fingers, and adapted to run idle when the first set of fingers are in operation but coming into action upon the reverse movement of said shaft after the displacement axially of said shaft when the first set of fingers will run idle in both directions.

14. In a computing machine having carrying mechanism, a shaft for the carrying mechanism, comprising a plurality of fingers radially projecting from said shaft and disposed relative to each other in a spiral, and a like number of radial fingers similarly mounted on said shaft, but arranged in an oppositely running spiral to the first mentioned fingers, the first set of fingers operating during the adding process and the second acting reversely during the subtracting process.

15. In a computing machine having carrying mechanism, a shaft for the carrying mechanism, comprising a plurality of fingers radially projecting from said shaft and disposed relative to each other in a spiral; and a like number of radial fingers similarly mounted on said shaft but arranged in an oppositely running spiral from the first-mentioned fingers, said shaft being adapted to receive rotation in one direction from a driving rack and pinion, and a reverse rotation from the same rack coöperating with an oppositely acting pinion brought into engagement by axial displacement of said shaft.

16. In a computing machine having carrying mechanism, a shaft for the carrying mechanism comprising a plurality of fingers radially projecting from said shaft and disposed relative to each other in a spiral; said shaft having a clutch engaging a driving pinion when running in one direction and idling in the opposite direction; a second pinion adapted to engage the clutch similarly to the first pinion but acting reversely

thereto and said shaft only engaging one of said pinions at a time, the other running idle.

17. In a computing machine having carrying mechanism, a shaft for the carrying mechanism comprising a plurality of fingers radially projecting from said shaft and disposed relative to each other in a spiral; said shaft having a clutch engaging a driving pinion when running in one direction and idling in the opposite direction; a second pinion adapted to engage the clutch similarly to the first pinion but acting reversely thereto, and said shaft only engaging one of said pinions at a time, the other running idle, both pinions being simultaneously driven by a toothed rack; means for displacing said shaft axially with the object of releasing the clutch between the shaft and one of the pinions and making engagement with the other.

18. In a computing machine having carrying mechanism, a shaft for the carrying mechanism comprising a plurality of fingers radially projecting from said shaft and disposed relative to each other in a spiral; said shaft having a clutch engaging a driving pinion when running in one direction and idling in the opposite direction; a second pinion adapted to engage the clutch similarly to the first pinion, but acting reversely thereto, and said shaft only engaging one of said pinions at a time, the other running idle, both pinions being simultaneously driven by a toothed rack; means for displacing said shaft axially with the object of releasing the clutch between the shaft and one of the pinions and making engagement with the other, an eccentric at one end of said shaft revolving to cause axial displacement in one direction, and a spring at the opposite end of the shaft returning said shaft to its normal or adding position on turning the eccentric back into its first position.

The foregoing specification signed at Washington, D. C., this 5th day of July, 1911.

CARL A. JOERISSEN.

In presence of two witnesses—

EDWIN S. CLARKSON,
HERMAN JACOBSSON.
